[57] ABSTRACT

A predrying tunnel for the combustion chamber of a steam generator in which the cooling pipes of the steam generator comprise the walls of predrying tunnels and are arranged horizontally in a vertical superimposed array. The cooling pipes forming the walls of the predrying tunnels extend from gas port inlets at the top of the tunnels downwardly to the level of injection of coal into the predrying tunnels. Hot gases are drawn from the combustion chamber of the steam generator through the predrying tunnels to dry wet coal injected into the tunnel before it drops to a plurality of mills which pulverize the coal. A plurality of blowers coupled to the predrying tunnels draws the pulverized coal and gases from the tunnel and mills, and forces the gases and coal through the burners of the steam generator into the combustion chamber where the coal is ignited.

PREDRYING TUNNELS FOR MILL DRYING DEVICES

The present invention relates to steam generators, and in particular, to pipe-cooled predrying tunnels for a mill-drying device of the coal dust furnace type.

Predrying tunnels for steam generators are known in the prior art. See for example, West German Patent No. 969,609. Predrying tunnels, such as these, are generally disposed outside of the steam generator combustion chamber, and exhaust ports are provided in the combustion chamber walls to channel gases from the combustion chamber to the predrying tunnels. In order to cool these predrying tunnels, some of the pipes used to cool the combustion chamber of the steam generator are mounted on the inner surfaces of the predrying tunnels. The cooling pipes of each tunnel extend through openings in the combustion chamber cooling pipe wall, so that many cooling pipes may be used to cool the tunnels.

The above-described cooling pipe structure for the predrying tunnels is disadvantageous since the cooling pipes are heated asymmetrically when the mill-drying device is run at a low capacity, or when the mill-drying device is not operated. This asymmetrical heating of the cooling pipes occurs over the "cooling area" of each predrying tunnel, which extends from its combustion chamber gas inlet port to the level at which coal is injected into the predrying tunnel. In a continuously operating steam generator, the flow generated into steam by the steam generator is sensitive when the mill-drying device operates at a low capacity, and could possibly become instable. Asymmetrical admittance of heat to the cooling pipes is, thus, not desirable, and the predrying tunnel cooling pipes are limited to the exhaust outlet area of each tunnel, since the cooling pipes are heated by the flame of the furnace of the steam generator directly only at that area of the tunnels. It is not possible, therefore, to cool that portion of the predrying tunnels between the exhaust outlet of the tunnels and the level at which the coal is injected into the tunnels.

It is therefore an object of the present invention to provide a predrying tunnel for a mill-drying device of a steam generator in which the area of the predrying tunnels between the exhaust outlet thereof and the level of injection of the fuel thereinto is cooled during operation of the steam generator.

It is also an object of the present invention to provide a predrying tunnel for a mill-drying device of a steam generator in which the combustion chamber cooling pipes of the steam generator absorb heat generated in equal amounts while the mill-drying device operates at a low capacity.

It is still another object of the present invention to provide a predrying tunnel for a mill-drying device of a steam generator which is simple in design, easy to manufacture and efficient and reliable in its operation.

Accordingly, the present invention provides a predrying tunnel for a mill-drying device of a steam generator in which the cooling pipes utilized to cool the combustion chamber wall of the steam generator are distributed in equal lengths over the inner walls of the predrying tunnels so that the steam generator flow is channeled through the cooling pipes disposed in the predrying tunnels. Each of the cooling pipes surrounding the combustion chamber of the steam generator and dis-

posed on the inner walls of the predrying tunnels are continuous and equal in length. Thus, heat is admitted to the cooling pipes in equal amounts, when either one or more of the mill drying devices of the predrying tunnels are in operation or operate at a low capacity.

In the present invention, all bends in the cooling pipes are equal in length, and fewer pipes are required than with conventional predrying tunnels. The cooling pipes are easily manufactured, and since they have an even flow-through resistance, the flow characteristics through the pipes are stable. Furthermore, since the temperature of the cooling pipes in the predrying tunnels and the walls of the combustion chamber is maintained at a constant level, the predrying tunnels may be coupled to the combustion chamber walls and the pipes thereof may be welded tightly together. This eliminates the requirement of conventional predrying tunnels that a special carrier frame be provided for the tunnels around the combustion chamber.

It should be noted that the predrying tunnels of the present invention may be disposed either inside or outside of the combustion chamber walls of the steam generator. With either arrangement, the heat loss which occurs in the steam generator is less than that which occurs in conventional steam generators in which the predrying tunnels extend into free space. Furthermore, because of this optional configuration, the construction of the boiler frame for the steam generator and the mounting of the boiler frame, are both more inexpensive, faster and easier than with conventional steam generators, and "dead angles" may be used in the combustion chamber without producing a detrimental effect on the heat transfer which occurs in the combustion chamber, or on the combustion chamber flame.

Directing the flow of the steam generator through the cooling pipes of the predrying tunnels does not disturb the stability of the steam generator flow. The interior spaces of the predrying tunnels are separated from the combustion chamber by a vertical wall of cooling pipes, and openings are provided on the upper ends of the predrying tunnels to couple the tunnels with the combustion chamber. The tunnels are not coupled to the combustion chamber at their lower ends.

The wall of cooling pipes separating the combustion chamber from the interior of the predrying tunnels serves both as a heating face for the combustion chamber and as a cooling face for the predrying tunnels. This wall separating the tunnel and the combustion chamber comprises a vertical array of two columns of pipes, the number of which is the same on both sides of the wall. Each cooling pipe which forms the cooling face of the predrying tunnels has the same length, so that each pipe forming the cooling face of the predrying tunnels is heated by the same amount. This construction prevents instability of the flow of the steam generator. The total flow of the steam generator is channeled through the cooling pipes of the predrying tunnels in order to prevent instability of the flow caused by a unilateral change in the heating of the wall of cooling pipes separating the combustion chamber from the interior of the predrying tunnels. With the above-described construction of the predrying tunnels, a single wall of cooling pipes may be utilized to construct a single predrying tunnel and separate its interior from the combustion chamber of the steam generator. The width of such a tunnel is designed so that the tunnel capacity is sufficient to meet the requirements of the steam generator.

Other objects and features of the present invention will become apparent from the following detailed description taken in connection with the accompanying drawings which disclose several embodiments of the invention. It is to be understood, however, that the drawings are designed for the purpose of illustration only and are not intended as a definition of the limits and scope of the invention.

In the drawings, wherein similar reference characters denote similar elements throughout the several views:

FIG. 1 is a top cross-sectional view of the combustion chamber of a steam generator constructed in accordance with the present invention, taken along section 1—1 of FIG. 2;

FIG. 2 is a cross-sectional side view of the combustion chamber, taken along section 2—2 of FIG. 1;

FIG. 3 is an enlarged top cross-sectional view of one embodiment of a predrying tunnel constructed in accordance with the present invention; and

FIG. 4 is an enlarged top cross-sectional view of another embodiment of a predrying tunnel constructed in accordance with the present invention.

Referring to the drawings, there is shown a vertically disposed combustion chamber 1 for the steam generator of the present invention. The combustion chamber includes pipe walls 2 which consist of a continuous length of a pipe 4 coiled in a rectangular shape around the combustion chamber and superimposed over itself vertically. The vertically-disposed array of pipes are welded together so as to be gas impermeable, and are suspended from the upper portion of a boiler frame 3. The mounting apparatus 4 of the pipes is known in the art and presents no problem to persons of ordinary skill in the art. Pulverized wet coal, such as, for example, bitumen coal, having a water content greater than 35 percent, is burned in combustion chamber 1 to produce heat for the steam generator. To facilitate easy burning of the coal, the coal is dried by hot gases drawn from the combustion chamber of the steam generator, and pulverized in a mill, before it is injected into the combustion chamber of the steam generator. Hot gases produced by the flames in the combustion chamber of the steam generator are drawn from the combustion chamber through predrying tunnels to the mill used to pulverize the coal. The coal to be burned in the combustion chamber is also drawn through the predrying tunnels to the mill so that the wet coal is dried while it drops through the tunnels. Hence, these tunnels are known by those skilled in the art as "predrying tunnels in a mill-drying device." Suction blowers draw the hot gases from the combustion chamber and force the gases and the pulverized coal to the mill. From there, the gases and coal are forced through burners into the combustion chamber where the coal is ignited.

The predrying tunnels of the present invention are cooled by a plurality of continuous cooling pipes, through which the flow of the steam generator is channeled, between the gas intake ports of the tunnels and the level of the predrying tunnels at which the wet coal is injected into the tunnels to be dried by the gases as it drops downwardly towards the mills. As shown in FIG. 1, continuous pipe 4 forms a combustion chamber wall through which the steam-water mixture of the steam generator flows in the direction of arrow 5. Pipe 4 is coiled around combustion chamber 1 in a continuous spiral, and is bent to form sections 6 and 7. Continuity of the pipe is maintained through these bends. In

FIG. 2, the cooling pipes have not been illustrated to preserve clarity of the drawings.

As shown in detail in FIG. 3, pipe 4 is bent to form sections 6, which are of equal length. Sections 6 form a vertical wall comprising two adjacent columns of pipes welded at one end to the wall of pipes around the combustion chamber so as to form a plurality of predrying tunnels 8. Sections 7 of the pipe, disposed adjacent heat insulation material 20, form the outer walls of predrying tunnels 8 and are also equal in length. Instability in the flow of the steam-water mixture of the steam generator is prevented by insuring that the pipe sections are of equal length. The entire flow of the steam-water mixture of the steam generator is channeled through cooling pipe sections 6 and 7 of the predrying tunnels.

Hot gases produced by the flame in the combustion chamber are drawn off by gas intake ports 9 which are coupled to the upper portions of predrying tunnels 8.

20 The lower ends of the predrying tunnels are not coupled to the combustion chamber and are closed off by plates 10. Predrying tunnels 8 are coupled to lateral tunnels 11 in which the wet coal is injected by feeding means 12, which may be a chute. Predrying of the coal begins as the wet coal drops through tunnel sections 13. The coal drops into mills 14, which are paddle mills, for further pulverization and drying. The mills also include larger paddle wheels 15 which also pulverize the coal, and draw out the gas and the coal dust from mills 14.

25 Paddle wheels 15 draw the hot gases from the combustion chamber 1 through ports 9, tunnels 8, 11 and 13 into mills 14. Tunnels 8 are cooled by the cooling pipes as the gases are drawn therethrough. The pulverized, dried coal is forced by paddle wheels 15 upwardly through feed pipes 16 to burners 17, which inject the coal into combustion chamber 1 with the cooled gases. Air is fed to burners 17 through air feed pipes 18 to aid in the combustion and ignition of the pulverized coal. Air supply couplings 19 are also coupled to tunnel sections 13 to regulate the drying temperature by admitting cool air in controlled amounts.

30 The predrying tunnels are constructed wide enough so that each may be provided with two predrying tunnel sections 11 and 13 and two mill-drying and blower devices 14 and 15. The amount of the coal dust and gas which is injected by burners 17 into combustion chamber 1 is adjusted by regulating the air supply to each of the predrying tunnels and burners. Thus, the apparatus may be adjusted to compensate for the effects produced when one or more of mills 14 is inoperative or operating at a low capacity. And, although the heating of cooling pipes 6 and 7 in the predrying tunnels is different, heat is admitted in equal amounts to pipe walls 2 between cooling pipes 6 and 7 since each of the pipe walls is of the same length. The superimposed arrangement of the cooling pipes between the predrying tunnels also distributes the irregularities of the heating process to the total length of pipe 4.

35 In FIG. 4, another embodiment of a predrying tunnel is disclosed. In this embodiment, pipe 4 is bent in a circular coil and is disposed within the heat insulation material 20 of pipe walls 2. Predrying tunnels 8 formed by these coils are substantially the same as the above-described predrying tunnels. Tunnels 8 comprise a plurality of circular coils superimposed upon each other, each coil being of the same length to prevent instability of the flow through the cooling pipes.

The materials used to construct the steam generator combustion chamber described above may be of any suitable conventional type. Selection of these materials will present no problem to those persons skilled in the art.

When predrying tunnels are constructed in accordance with the present invention, it is not necessary to provide a fire-proof lining or casing for the interior of the tunnels. Slag also does not form on the walls of the predrying tunnels, and the air flow between the walls does not, therefore, become constricted. The predrying tunnels are mounted on the mounting frame of the steam generator along with pipe walls 2, and thus do not require separate mounting means. The heat loss of a combustion chamber constructed as described above is also reduced since the predrying tunnels are encompassed in the heat insulation material 20 of the steam generator combustion chamber.

The temperature of the hot gases drawn off from the combustion chamber for drying the wet coal is lowered by the admittance of cool air by coupling 19, without any additional air supply, to a temperature which is compatible with the materials of the mills 14. "Dead angles" also may be used for the predrying tunnels, and as a result, combustion chamber 1 may be constructed as a vertically rotating burner chamber of rectangular shape.

Cooling pipe sections 6 and 7 of the predrying tunnels form heating faces which reduce the heat in combustion chamber 1 and prevent the steam-water mixture flowing through pipe walls 2 from completely evaporating. When the mills are operating at a low load capacity, i.e., when one or more of the mills are switched off, cooling pipe sections 6 and 7 function as unheated throttle areas so that sections of pipe 4 within pipe walls 2 are heated more intensely and move evenly and the flow stability of the steam-water mixture is improved. As a result of this improvement of the flow stability during operation of the mills at low load capacity, mills 14 are operated more economically. With the apparatus of the present invention, no disadvantages are present if one or more of the entire group of mills 14 is completely shut off while the remainder of the mills work at full load capacity. Furthermore, in order to regulate the flow through the steam generator, it is no longer necessary with the apparatus of the present invention to evenly distribute the capacity to all of mills 14.

While only several embodiments of the present invention have been shown and described, it will be obvious to those persons skilled in the art that many changes and modifications may be made thereunto without departing from the spirit and scope of the invention.

What is claimed is:

1. A predrying tunnel for the combustion chamber of a steam generator, comprising:

a plurality of horizontally disposed, vertically superimposed, cooling pipes, disposed in spiral arrangement around the combustion chamber of the steam generator, said spiral arrangement of said pipes comprising one continuous pipe length and forming pipe walls on the interior surfaces of the combustion chamber, and being bent at at least one corner of the combustion chamber so as to form at least one vertical tunnel within the combustion chamber of the steam generator;

means, coupled to said vertical tunnel, for guiding gases from the combustion chamber to said tunnel; at least one additional cylindrical tunnel coupled to said vertical tunnel in the combustion chamber; means, for injecting fuel into said cylindrical tunnel; and

means, coupled to said cylindrical tunnel, and to the combustion chamber, for pulverizing fuel injected into said cylindrical tunnel, and drawing air from the combustion chamber through said vertical tunnel and said cylindrical tunnel and forcing said air and pulverized fuel into the combustion chamber of the steam generator.

2. The predrying tunnel as recited in claim 1, wherein said vertical tunnel is triangular in shape, one wall of said vertical tunnel comprising at least two adjacent vertical walls of superimposed pipes for separating the combustion chamber from the interior of said vertical tunnel.

3. The predrying tunnel as recited in claim 2, wherein said fuel pulverizing means comprises a paddle wheel mill, disposed at the bottom of said cylindrical tunnel, for pulverizing fuel injected into said cylindrical tunnel.

4. The predrying tunnel as recited in claim 3, wherein said paddle wheel mill further comprises blower means, for drawing gases from the combustion chamber through said vertical tunnel and said cylindrical tunnel into said mill, and forcing the pulverized fuel and said gases into the combustion chamber of the steam generator.

5. The predrying tunnel as recited in claim 4, wherein said cylindrical tunnel is coupled to the combustion chamber of the steam generator by a plurality of elongated pipes and combustion chamber burners which guide the gases and pulverized fuel from said mill to the combustion chamber.

6. The predrying tunnel as recited in claim 1, wherein said vertical tunnel is circular in shape, and comprise a vertically disposed array of horizontal coils.

7. The predrying tunnel as recited in claim 1, wherein said cooling pipes comprising the walls of said vertical tunnel are disposed between the points at which said cylindrical tunnel and said means for guiding gases from the combustion chamber into said vertical tunnel are coupled to said vertical tunnel.
